UNITED STATES PATENT OFFICE

EDGAR PLADSON, OF FLINT, MICHIGAN

POST PULLER

Application filed April 12, 1930. Serial No. 443,784.

This invention relates to certain new and useful improvements in pullers or extricators for stumps, posts and the like.

One of the principal objects of the invention consists of a fulcrum lever designed for biting engagement with its work in all stages of the lifting action thereof.

Another object of the invention consists of means for holding the fulcrum lever in position for use.

An additional object of the invention embodies a support for the operating lever having adjustable connection therewith.

More specifically stated the support is so disposed as to provide a floating fulcrum for the lever whereby the latter will follow the work in the event the latter should deviate from the intended direction of lift.

With the above and other objects in view, the invention further consists of the following novel features and details of construction, to be hereinafter more fully described, illustrated in the accompanying drawing and pointed out in the appended claims.

In the drawing:

Figure 1 is a side elevation of the invention as applied for use.

Figure 2 is a top plan view thereof.

Figure 3 is a rear elevation of the invention with the operating lever in section.

Referring to the drawing in detail wherein like characters of reference denote corresponding parts, the reference character 10 indicates generally a foot or base plate having the laterally projecting attaching flanges 11 of spaced parallel upstanding plate members 12 secured thereto. A fastening element, such as indicated at 13, horizontally disposed between and having connection with the spaced plate members 12 carries a spacing thimble 14 upon that portion thereof disposed between the adjacent faces of the plate members 12 whereby said thimble will coact with the attaching flanges 11 in the preservation of a space of equal width throughout the

entire length of the form of support. It will, of course, be obvious that any suitable anchorage, not shown, may be employed for rigidly securing the plate members 12 in adjacent relation with respect to the article to be extracted, and the illustration of such anchorage is, therefore, not deemed necessary.

The plate members 12 are provided with aligned pocket portions upon the inner side edges thereof generally designated as at 15 having the forward walls 16 outwardly and downwardly inclined for communication with a semi-circular rearwardly extending wall portion 17 which forms one side of a wall portion 18 extending well within the entrance 60 for pocket portions 15 to restrict, not only the entrance of the extremities of a cross or fulcrum pin 19, but also to prevent accidental displacement thereof during the lifting action about to be described.

The lifting lever, alluded to in the foregoing and generally designated as at L, is provided with a straight portion 19' projected within and through the space preserved between the plate members 12 and outwardly therebeyond for appreciable distances, in both directions. An upwardly, rearwardly and obliquely inclined portion 20 formed as a continuation of the straight portion 19 terminates to provide a hand engaging portion 21 nearly following the same plane of the straight portion 19'. The forward or outwardly projecting end of the lever L is of arcuate shape and toothed as at 21 for biting engagement with its work whether the latter be steel or wooden posts. Due to the specific configuration or contour of the pockets 15, the fulcrum pins 19 are allowed to shift laterally within the pockets during the operation of the fulcrum lever as the latter is shifted with the work, whereby said lever will move with the work to prevent the disengagement thereof from the work, and to retain the arcuate shaped end 21 of the lever with the work. The instant post puller will

prove more effective for the purpose of lifting stumps, posts, and the like, in that the device will allow the post to be extracted in the same plane that the post stands. In this 5 manner, no distorted motions will be imparted to the post whereby the latter will be extricated more expeditiously from the ground. It will, therefore, be seen that the device shown is of an automatic nature to change the 10 locus of the fulcrum in order that the toothed portions will remain engaged with the work through the entire swing of the lever. As a means of convenience in the lifting action and to preserve biting engagement of the 15 toothed portions 21 with the immediate surface of the work to be elevated or otherwise extricated, I provide a chain 22 having swivel connection at one end with the lever L and detachable connection at its other end with 20 an adjusting hook 23. It is obviously apparent that the cross pin 19 is to be carried by the lever L.

As will be noted from the illustration in 25 Figure 1 of the drawing, the chain 22, toothed portions 21, cross pin 19 and the particular shaped pockets 15 will coact in the compensating for possible deviation of the work being lifted by following the inclination thereof whereby the toothed portions 21 will remain in biting engagement therewith. It is further noted that the chain connection 22 will gradually tighten up as the angularity thereof with respect to its initial position is changed or otherwise altered whereby the 30 teeth 21 will be more deeply embedded in the work to obviate slipping or accidental displacement.

The invention is susceptible of various 35 changes in its form, proportions and minor 40 details of construction, and the right is herein reserved to make such changes as properly fall within the scope of the appended claims.

Having described the invention, what is claimed is:

45 1. A jack construction comprising a base, spaced parallel standards rising from said base, each of said standards having provided in one of the vertical edges thereof a plurality of pockets, the pockets of the standards 50 aligning horizontally with one another, the walls of each pocket terminating in a semi-circular portion, a fulcrum lever, a cross pin carried by said lever and loosely journaled in the semi-circular portion of said pockets for 55 allowing the cross pin to shift in the pockets, whereby said lever will move with the work, and an arcuate-shaped tooth portion formed on one end of said lever.

60 2. A jack construction comprising spaced parallel standards having aligned pocket portions terminating in a semi-circular portion, a fulcrum lever between said standards, and provided with a cross pin loosely journaled within the semi-circular portions of the 65 pocket, and an arcuate-shaped tooth portion

formed on one end of said lever, the diameter of the semi-circular portion of the pockets being greater than the diameter of the fulcrum pins allowing the latter to shift laterally within said semi-circular portions of the pockets of the lever for forcing the arcuate tooth portion thereof in engagement with the work during the full swinging action of the lever.

In testimony whereof I affix my signature. 75
EDGAR PLADSON.
